UNITED STATES PATENT OFFICE

2,433,934

TIE DEVICE FOR WALL FORMS

Arthur H. Symons, Chicago, Ill.

Application June 24, 1944, Serial No. 541,921

8 Claims. (Cl. 25—131)

1

The present invention relates generally to tie devices. More particularly the invention relates to that type of tie device which is adapted for use in tying together and holding against separation a pair of laterally spaced upstanding forms for concrete walls or like structures and as its main or principal parts comprises: (1) a combined tie and spread rod which extends horizontally between the two forms and has one end thereof anchored to one of the forms and its other end provided with an enlargement at its extremity and arranged so that it extends through a hole in the other form and the enlargement is disposed adjacent a single reenforcing beam, such as a stud or wale on the outer face of said other form; (2) a bracket which fits against, and is secured to, the reenforcing beam; and (3) a member which is slidably mounted on the bracket, is adapted when slid in one direction to interlock with the enlargement, and serves when in its operative position wherein it is in interlocked relation with the enlargement to connect the bracket to the rod and thus maintain the other form in its proper or desired position with respect to the one form.

One object of the invention is to provide a tie device of this type which is an improvement upon, and has certain advantages over, previously designed devices for the same purpose, including that which is disclosed in, and forms the subject matter of, an application for United States Letters Patent filed by me on even date herewith, and serially numbered 541,920.

Another object of the invention is to provide a tie device of the aforementioned type which is characterized by simplicity of design, cheapness of construction and facility of assembly and dismantlement.

Another object of the invention is to provide a tie device of the type and character under consideration in which the enlargement at the extremity of the end of the rod that extends through the form with the reenforcing beam is in the form of a U-shaped loop, and the slidably mounted member is in the form of a wedge shaped plate and has a bifurcated small end which when the member is in its operative position straddles the outer end of the loop and serves to lock the bracket against longitudinal displacement in either direction relatively to the combined tie and spreader rod.

A further object of the invention is to provide a tie device of the last mentioned character in which the loop equipped end of the combined tie and spreader rod extends through a transverse

2

aperture in the reenforcing beam and the bracket and wedge shaped member are so constructed and arranged that when the member is in its operative position wherein the small end thereof straddles the outer end of the loop no forces are set up tending to roll or rock the reenforcing beam relatively to the adjacent form.

A still further object of the invention is to provide a tie device which is generally of new and improved construction and effectively and efficiently fulfills its intended purpose.

Other objects of the invention and the various advantages and characteristics of the present tie device will be apparent from a consideration of the following detailed description.

The invention consists in the several novel features which are hereinafter set forth and are more particularly defined by claims at the conclusion hereof.

20 In the drawings which accompany and form a part of this specification or disclosure and in which like letters and numerals of reference denote corresponding parts throughout the several views:

25 Figure 1 is a fragmentary perspective view showing a pair of laterally spaced upstanding wall forming forms having applied thereto a tie device embodying the invention;

Figure 2 is a perspective view of the wedge shaped member;

Figure 3 is a perspective view of the combined tie and spreader rod;

Figure 4 is a perspective view of the bracket;

Figure 5 is a horizontal section showing the device in its operative position; and

Figure 6 is a vertical section taken on the line

6—6 of Figure 5 and illustrating in detail the manner in which the wedge shaped member contacts with the outer end of the loop and the bracket so as to lock the bracket against longitudinal displacement in either direction relatively to the combined tie and spreader rod.

The tie device which is shown in the drawings constitutes the preferred form or embodiment of the invention. It is adapted for use in connection with a pair of upstanding wall forming forms F and F¹ and comprises a combined tie and spreader rod 1, a bracket 8 and a wedge 9. The forms are disposed in laterally spaced relation and are adapted to have concrete poured therebetween for wall forming purposes. As well understood in the art, the forms are removed after hardening or setting of the concrete. The form F comprises a comparatively thin flat composite wooden panel f and an exteriorly disposed wooden re-

enforcing beam f^1 in the form of a stud or wale. Such beam extends horizontally, as shown in Figure 1. It serves not only to reenforce the panel f but also to align the planks thereof and suitably secured by nails or other attaching devices (not shown) to the outer face of said panel f .

The combined tie and spreader rod 7 extends horizontally between the two forms F and F^1 and is circular in cross section. It is disposed at right angles to the forms and has one end thereof extending through the form F^1 and anchored to the latter in any suitable manner. The other end of the rod extends through a hole f^3 in the panel f and a horizontal transversely extending aperture f^4 in the reinforcing beam f^1 . The outer extremity of the end of the combined tie and spreader rod 7 that projects through the aforementioned hole and aperture projects a comparatively small distance beyond the outer face of the reinforcing beam and is bent laterally and then inwards to form a loop 10 . The aperture f^4 in the reinforcing beam f^1 is in alignment or registering relation with the hole f^3 in the panel f . The aperture and hole are of sufficient width to permit the loop 10 to pass therethrough in connection with assembly of the combined tie and spreader rod 7 with respect to the form F . The portion of the rod that is directly inwards of the hole f^3 in the panel f has a smooth cylindrical contour and possesses no enlargement, washer or crosspin in abutment with the inner face of the panel f .

The bracket 8 is in the form of a plate metal stamping and fits against the outer face of the reinforcing beam F^1 . It is horizontally elongated and consists of a vertically extending wall 11 and a horizontally extending wall 12 . The wall 11 fits flatly against the outer face of the reinforcing beam f^1 and is fixedly secured in place by way of a pair of lag screws 13 . The shanks of the screws extend through horizontally elongated slots 14 in the ends of the wall 11 and project into the outer portion of the reinforcing beam. The central portion of the vertically extending wall 11 of the bracket is provided with a horizontally elongated slot 15 which is in registry with the outer end of the transverse aperture f^4 in the reinforcing beam f^1 and has the loop 10 of the rod 7 projecting therethrough. When the device is assembled, the loop 10 , as shown in Figures 1, 5 and 6, is disposed horizontally and projects through and outwards of the horizontally elongated slot 15 in the central portion of the wall 11 of the bracket. The horizontally extending wall 12 is formed integrally with, and projects outwards from, the upper margin of the vertically extending wall 11 . The central portion of the wall 12 is provided with a slot 16 and this extends at right angles to the wall 12 and is vertically aligned with the central portion of the loop receiving slot 15 in the wall 11 . As shown in Figure 4 the inner end of the slot 16 terminates adjacent the outer face of the vertically extending wall 11 of the bracket. In addition to the walls 11 and 12 the bracket 8 comprises an upstanding metallic lug 17 . This lug is welded to, and projects upwards from, the central portion of the upper margin of the vertically extending wall 11 of the bracket and is so positioned that the outer face thereof is flush with the outer face of said wall 11 .

The wedge 9 is stamped from flat plate metal and is mounted for vertical sliding movement in the slot 16 in the central portion of the horizon-

tally extending wall 12 of the bracket. It is arranged so that the small end thereof projects downwards. The slot 16 is of such length that when the wedge 9 is driven downwards the upper end of the wedge fits snugly in the slot 16 . Said small end of the wedge is provided with an elongated longitudinally extending notch 18 in order that it is bifurcated and embodies a pair of laterally spaced arms 19 . When the wedge is driven downwards while the loop 10 projects through the slot 15 in the vertically extending wall 11 of the bracket the arms 19 are brought into straddled relation with the outer end of the loop 10 with the result that the wedge so connects the bracket to the rod that it is locked against longitudinal displacement in either direction relatively to the rod. When the wedge is in its operative position the outer end of the loop 10 is disposed in the upper end of the notch 18 and the inner edge of the wedge fits flatly against the outer face of the lug and the vertically extending wall 11 of the bracket. The width of the upper end of the notch 18 is the same as the diameter of the combined tie and spreader rod with the result that the outer end of the loop fits snugly in the upper end of the notch when the wedge is in its operative position. The lower end of the notch 18 is downwardly flared in order to facilitate entry of the outer end of the loop into it during downward driving of the wedge. When the wedge is in its operative position the upper portion of the inner edge of the wedge engages the outer face of the lug 17 and the lower portion of the inner edge of the wedge engages the outer face of the vertically extending wall 11 of the bracket with the result that the wedge is effectively held against rocking or tilting relatively to the bracket. By reason of the fact that the loop equipped end of the rod 7 extends through the transversely disposed aperture f^4 in the reinforcing beam f^1 the forces which result from driving of the wedge 9 into its operative position do not tend to roll or rock the beam relatively to the panel f . When it is desired to remove the form F the wedge 9 is driven upwards until it is disengaged from the loop 10 . In order to maintain the wedge in slidably connected relation with the upper side wall of the bracket the lower end of the inner arm 19 is provided with a crosspin 20 . The length of this pin is slightly greater than the width of the slot 16 . The width of the space within the loop 10 is such that the pin is free to pass through the loop when the wedge is shifted upwards in connection with release thereof from the loop.

When it is desired to use the tie device the form F^1 is first erected or properly positioned and the adjacent end of the combined tie and spreader rod 7 is anchored thereto. Thereafter the form F is positioned in opposed relation with the form F^1 and is manipulated so as to position the hole f^3 in the panel f in registry with the loop 10 of the rod 7 . After such manipulation of the form F the latter form is shifted bodily towards the form F^1 until the loop 10 is disposed directly outwards of the horizontal slot 15 in the central portion of the vertically extending wall 11 of the bracket. In connection with inward shift of the form F the wedge 9 is held so that the small or lower end thereof is above the slot 15 . After proper positioning of the form F the wedge 9 is driven downwards so as to bring the bifurcated lower end thereof into straddled relation with the outer end of the loop 10 and its upper end in seated relation with the slot 16 . As heretofore

pointed out, when the wedge is driven into its operative position the upper end thereof fits snugly in the slot 16 and when the device is fully assembled the form F is locked or held against longitudinal displacement in either direction relatively to the combined tie and spreader rod 7. After assembly of the device concrete is poured into the space between the two forms. After hardening or setting of the concrete the forms are removed from the concrete formed wall. In connection with removal of the form F the wedge 9 is driven upwards until it is disengaged from the loop 10. Thereafter the form F¹ is shifted laterally away from the wall. After removal of the form F the end portion of the rod 7 having the loop 10 is severed from the central portion of the rod which is embedded in the wall.

The herein described tie device effectively and efficiently fulfills its intended purpose and may be assembled and dismantled with facility. It is essentially simple in design and construction and hence may be manufactured at a low and reasonable cost. By reason of the fact that the wedge when in its operative position is locked to the bracket and has its bifurcated end in snug straddled relation with the outer end of the loop on the rod there can be no slippage whatsoever of the form F with respect to the rod. The device is adapted or designed to be used with like devices in holding the two forms against separation during a concrete pouring operation.

Whereas the device has been described as comprising a single bracket and a single wedge at one end of the combined tie and spreader rod it is to be understood that the other end of the rod may be connected to the form F¹ by providing said other end of the rod with a loop and utilizing in connection with such loop another bracket and another wedge, as shown in Figures 1 and 5. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. The combination with a wall forming form with a transverse opening therethrough, of a combined tie and spreader rod having one end thereof extending through the opening and provided at its extremity and adjacent the outer face of the form with a laterally extending part, a bracket connected fixedly to said outer face of the form at a point adjacent the opening, and an elongated member mounted on the bracket so that it extends at right angles to the rod, is slideable longitudinally to and from one end of the rod, and is locked or held against lateral displacement with respect to the bracket when it is slid as far as possible towards said one end of the rod, having the end thereof nearer the rod bifurcated in such manner as to provide an inner and an outer arm, and adapted when slid towards the rod to have the two arms brought into such straddled relation with said laterally extending part as positively to lock the bracket and form against longitudinal displacement in either direction relatively to said rod.

2. The combination with a wall forming form with a transverse opening therethrough, of a combined tie and spreader rod having one end thereof extending through the opening and provided at its extremity and adjacent the outer face of the form with a loop, a bracket connected fixedly

to the outer face of the form and disposed adjacent the opening, and an elongated member mounted on the bracket so that it extends at right angles to the rod, is slideable longitudinally to and from the one end of the rod and is locked or held against lateral displacement with respect to the bracket when it is slid as far as possible toward said one end of the rod, having the end thereof nearer the rod bifurcated in such manner as to provide an inner and an outer arm, and adapted when slid towards the rod to have the two arms brought into such straddled relation with the outer portion of the loop as positively to lock the bracket and form against longitudinal displacement in either direction relatively to the rod.

3. The combination with a wall forming form in the form of a panel and an externally disposed reenforcing beam and with aligned transversely extending openings in the panel and beam, of a combined tie and spreader rod having one end thereof extending through the openings and provided at its extremity and adjacent the outer face of the beam with a laterally extending part, a bracket connected fixedly to said outer face of the beam at a point adjacent the opening, and an elongated member mounted on the bracket so that it extends at right angles to the rod, is slideable longitudinally to and from one end of the rod, and is locked or held against lateral displacement with respect to the bracket when it is slid as far as possible towards said one end of the rod, having the end thereof that is nearer the rod bifurcated in such manner as to provide an inner and an outer arm, and adapted when slid towards the rod to have the two arms brought into such straddled relation with the laterally extending part of the rod as positively to lock the bracket and form against longitudinal displacement in either direction relatively to the rod.

4. A tie device designed for use in connection with a wall forming form with a transverse opening therethrough, and comprising a combined tie and spreader rod having one end thereof extending through the opening and provided at its extremity and adjacent the outer face of the form with a laterally extending part, a bracket connected fixedly to the outer face of the form at a point adjacent the opening and embodying a substantially flat wall fitting flatly against said outer face of the form, and a side wall connected to, and projecting outwards from, the first mentioned wall and provided with a transverse slot in alignment with the laterally extending part of the rod, a wedge shaped member extending slidably through the slot, having the small end thereof nearer said laterally extending part and longitudinally notched to provide a bifurcation, and adapted when slid toward the rod to have the bifurcation straddle the part in such manner as to lock the bracket and form against longitudinal displacement with respect to the rod.

5. A tie device designed for use in connection with a wall forming form in the form of a panel and an exteriorly disposed panel and reenforcing beam, and with aligned transversely extending openings in the panel and beam, and comprising a combined tie and spreader rod having one end thereof extending through the openings and provided at its extremity and adjacent the outer faces of the beam with a loop, a bracket connected fixedly to the beam at a point adjacent the loop, and embodying a wall fitting against said outer face of the beam and provided with a

loop receiving opening in alignment with said openings in said panel and beam, and a single side wall connected to, and projecting outwards from, one margin of the first mentioned wall and provided with a transversely extending slot in alignment with the loop, and a wedge shaped member extending slidably through the slot, having the small end thereof nearer the loop and longitudinally notched to provide a bifurcation, and adapted when slid in the direction of the rod to have the bifurcation straddle the outer end of the loop in order to lock the bracket against longitudinal displacement with respect to the rod.

6. A tie device designed for use in connection with a wall forming form with a transverse opening therethrough, and comprising a combined tie and spreader rod having one end thereof extending through the opening and provided at its extremity and adjacent the outer face of the form with a loop, a bracket connected to the form at a point adjacent the opening and embodying a substantially flat wall fitting flatly against the outer face of the form, and a side wall connected to, and projecting outwards from, one margin of the first mentioned wall and provided with a transverse slot in alignment with the loop and with one end thereof terminating at the outer face of said first mentioned wall, and a wedge shaped member extending slidably through the slot, having the small end thereof nearer the loop, and adapted when slid toward the rod to extend through the loop and lock the bracket and form against longitudinal displacement with respect to the rod, said bracket also embodying a lug-like extension connected to said one margin of the first mentioned wall, disposed in coplanar relation with the latter, extending away from the side wall and having the outer face thereof forming with the outer face of said first mentioned wall a comparatively large bearing surface for engagement with the inner side edge of the wedge shaped member and preventing longitudinal tilting or rocking of the wedge shaped member relatively to the bracket when the wedge shaped member is in its operative position.

7. A tie device designed for use in connection with a wall forming form with a transverse opening therethrough, and comprising a combined tie and spreader rod having one end thereof extending through the opening and provided at its extremity and adjacent the outer face of the form with a loop, a bracket connected to the form at a point adjacent the opening, embodying a substantially flat wall fitting against said outer face of the form and provided with a loop receiving opening in alignment with the opening in the form, and a single side wall connected to, and projecting outwards at right angles from, one margin of the first mentioned wall, and provided with a transverse slot in alignment with the loop and with the inner end thereof terminating adjacent the outer face of said first mentioned wall, and a wedge shaped plate extending slid-

ably through the slot, having the small end thereof adjacent the loop, and adapted when slid toward the rod to extend through the loop and lock the bracket and form against longitudinal displacement with respect to the rod, said bracket also embodying a lug-like extension connected to said one margin of the first mentioned wall, disposed in coplanar relation with said first mentioned wall, projecting away from the side wall, and having the outer face thereof forming with the outer face of said first mentioned wall a comparatively large bearing surface for engagement with the inner side edge of the plate and preventing longitudinal tilting or rocking of the plate relatively to the bracket when the plate is in its operative position.

8. A tie device designed for use in connection with a wall forming form with a transverse opening therethrough, and comprising a combined tie and spreader rod having one end thereof extending through the opening and provided at its extremity and adjacent the outer face of the form with a loop, a bracket connected to the form at a point adjacent the opening and embodying a substantially flat wall fitting flatly against the outer face of the form, and a side wall connected to, and projecting outwards from, one margin of the first mentioned wall and provided with a transverse slot in alignment with the loop and with one end thereof terminating at the outer face of said first mentioned wall, and a wedge shaped plate extending slidably through the slot, having the small end thereof nearer the loop and longitudinally notched to provide a bifurcation, and adapted when slid toward the rod to have the bifurcation straddle the outer part of the loop in such manner as positively to lock the bracket and form against longitudinal displacement in either direction with respect to the rod, said bracket also embodying a lug-like extension connected to said one margin of the first mentioned wall, disposed in coplanar relation with the latter, extending away from the side wall and having the outer face thereof forming with the outer face of said first mentioned wall a comparatively large bearing surface for engagement with the inner side edge of the plate and preventing rocking of the plate relatively to the bracket when the plate is in its operative position.

ARTHUR H. SYMONS.
